UNITED STATES PATENT OFFICE.

JOSEPH WILLIAM HELTZEL, OF WARREN, OHIO.

CONCRETE-GROOVING DEVICE.

Application filed March 11, 1926. Serial No. 93,977.

The present invention relates to the building of concrete roads or other concrete surfacing structures, and the invention aims to provide a novel means for controlling the 5 breaking or fracturing of the concrete after it has set, and such means may also be used for making traffic lines and joints in concrete roads or other surfacing structures.

As well known, roads and other surfacing structures composed of concrete will crack along irregular lines due to traffic or climatic changes, and a concrete road will usually become fractured along irregular lines lengthwise thereof due to the pressure and 10 weight on the opposite side portions of the road under heavy traffic, and also due to the heaving action of the ground or sub-base in freezing weather. To overcome the irregular breaking of the concrete it has been the 15 practice to install longitudinal vertical division plates along the line where the break is desired. These division plates are somewhat expensive, being embedded in the concrete, and extending from the sub-base to a point 20 close to or at the surface of the concrete. It has been a difficult problem to install such division plates along a straight or regular line, and even with the use of such division plates an irregular break occurs, which, however, 25 is not quite as objectionable as a natural break.

With the foregoing objections in view, it is an object of the present invention to control the breaking of the concrete or to make 30 a joint in the concrete which will be less expensive and more effective than the use of division plates as heretofore. With these ends in view, division plates or strips are used which are of less height than the division plates heretofore used, to provide for 35 economy, and to space the upper edges of the division plates or strips several inches below the surface of the concrete. These division plates or strips may also be installed more 40 quickly, with a saving in cost, inasmuch as they need not be accurately disposed on the sub-base. This obtains a saving both in material and in installation, and, moreover, the division plates or strips do not interfere 45 with the tamping or finishing off of the concrete above the division plates, as has occurred with the use of the ordinary division plates that extend to or adjacent the surface 50 of the concrete. The invention consists further in forming a groove in the surface of

the concrete above the division plates or strips. This groove may be formed quickly and accurately, so as to present a regular and accurate line, for purpose of appearance. After the concrete has hardened, it will 60 break between the groove and division plates or strips, said groove weakening the concrete above the division plates or strips so that the concrete, in cracking, will break along the line of the groove, which is the 65 line of least resistance in the fracturing of the concrete. In this way, the breaking or fracturing of the concrete is controlled, for producing a joint in the concrete which may also serve as a traffic line for dividing oppositely moving traffic.

A further object of the invention is the provision of a novel device for producing a groove or cut in the plastic concrete.

With the foregoing and other objects in 75 view, which will be apparent as the invention is more fully understood, the invention resides in the means as hereinafter described and claimed, it being understood that changes may be made within the scope of 80 what is claimed, without departing from the spirit of the invention.

The invention is illustrated in the accompanying drawings, wherein—

Figure 1 is a perspective view showing the 85 several steps of the method employed and also illustrating the groove forming device in use.

Fig. 2 is a plan view of said device.

Fig. 3 is an elevation of said device illustrating a portion of the road in cross section.

Fig. 4 is a perspective view illustrating a modified form of grooving device.

Fig. 5 is a perspective view illustrating a modified form of division plate or strip.

Figs. 6 and 7 are cross-sections of completed joints showing modifications in the division plates or strips.

Although the invention is described in connection with the building of a concrete road, 100 it will be understood that same may be used for other concrete surfacing structures for which the invention is suitable. When building a concrete road the side forms or rails 7 are disposed on the ground or sub-base 105 to define the sides or longitudinal edges of the road, and the grout is poured between said rails and the surface of the concrete finished in any well known manner.

In carrying out the present invention to 110

control the longitudinal breaking of the concrete along the center line of the road, division plates or strips 8 are placed on the sub-base along the line where the longitudinal break is desired. These strips 8 may be of thin sheet metal, so as to be inexpensive, and need only be of a height of two or three inches (more or less), so that their upper edges are spaced several inches below the surface of the concrete in the completed road. Such strips are therefore considerably cheaper than division plates heretofore used which extend from the sub-base to the upper surface of the concrete. It is unnecessary to locate the strips 8 along the desired line with extreme accuracy, so as not to require painstaking care in disposing said strips on the sub-base, thereby saving time as compared with the installation of ordinary division plates. The strips 8 are secured in place on the sub-base by means of stakes 9 driven into the sub-base, or other suitable means may be used for the purpose. The strips 8 have sockets 10 through which the stakes are driven. The strips 8 may be plain, so as to be cheap, and may even be composed of wood, fibre, paper and other materials.

The positioning of the strips 8 on the sub-base is the first step of the method, and the next step consists in the pouring of the concrete on the sub-base between the rails 7 and over the strips. Said strips are placed on the sub-base in advance of the concrete mixer as it advances along the roadway. The concrete is struck off, tamped and finished in any of the well known methods, and the strips 8 being located several inches below the surface of the concrete will not in any way interfere with the tamping and finishing of the concrete over said strips, which has caused difficulty with the use of division plates extending close to the surface of the concrete. The strips 8 are embedded in the lower portion of the concrete 11, thereby dividing the concrete at the bottom thereof.

The third step in the method consists in forming a groove or cut 12 in the surface of the concrete above the strips 8. This groove 12 may be formed in the concrete while it is still plastic, and it is possible to make the groove follow a definite straight or curved line, so as to produce a neat and finished job. This groove not only provides a traffic line along the center of the road for dividing oppositely moving traffic, but also controls, in connection with the strips 8, the breaking of the concrete after the concrete has set. The concrete will crack along the weakened portion between the strips 8 and groove 12, and even though the strips are not directly under the groove 12, the breaks will extend upwardly from said strips to the groove 12 due to the weakening of the concrete by said groove. As a result, the con-

crete will break accurately along the groove 12 although the breaks may be irregular below said groove. This irregular breaking of the concrete between the groove 12 and strips 8 is even of advantage in locking the adjacent edges of the opposite slabs or sections together against relative vertical displacement. The strips 8 being cheaper in cost and less expensive to install as compared with the division plates heretofore used, will provide for economy, and the groove 12 may be quickly formed in the surface of the concrete. It is also apparent that the strips 8 may be disposed transversely of the concrete with transverse grooves 12 above said strips, for producing transverse breaks or joints, and the strips and grooves may extend in different directions in various concrete surfacing structures for controlling breaks and producing joints.

The appliance shown in Figs. 1, 2 and 3 for producing the groove 13 comprises a truck to move along one of the rails 7. Such truck is composed of a longitudinal beam 13 mounted near its ends on the wheels 14 adapted to roll on the rail 7. Each wheel has an outer flange 15 to overlap the outer side of the rail, and disks 16 of sheet metal, preferably highly tempered steel, are bolted or otherwise secured to the inner sides of the wheels and have their edges formed to overlap the inner sides of the rail and to round off the corresponding outer corner of the concrete 11, as at 17. The wheels 14 will thus move along the rail, the flanges 15 and disks 16 holding said wheels in place on the rail, and the disks 16 will finish or round off the corresponding corner or edge portion of the concrete as the device is moved along the rail.

A bar 18 composed of channel iron or other suitable material extends across and is secured on the beam 13 between the wheels 14, and is connected to said beam by braces 19 and 19^a. Said bar 18 extends inwardly from the truck so as to move over the concrete, and carries the grooving trowel 20 at its inner terminal.

The trowel 20 comprises a top piece 21 composed of sheet metal and disposed longitudinally of the road, said piece 21 being secured to the bar 18, and having its end portions bent back downwardly, as at 22. A bottom piece or shoe 23 is secured to the end portions 22 of the top piece 21 and is curved so as to present a convexed surface to the concrete. The bottom piece or shoe 23 is resilient so as to be capable of being sprung toward a straight line position when pressed on the concrete, and said shoe has a longitudinal rib 24 depending therefrom between its edges to produce the groove 12 in the surface of the concrete. The shoe 23 will smooth off the surface of the concrete at the opposite sides of the groove. The top piece

21 is connected to the bar 18 by braces 25, and the trowel or tool 20 may be adjusted along the bar 18 to different position in order to space the groove 12 a desired distance from the corresponding side or edge of the road.

The bar 18 also projects outwardly a short distance beyond the beam 13, and an arch 26 is secured on the outer portion of said bar, 10 and its inner limb is connected by braces 26^a with the beam 13. Cross pieces 27 are secured on the arch 26 and handle rods 28 are secured to the pieces 27 at opposite sides of the arch 26 for conveniently moving the 15 device along the road by hand in either direction. A suitable weight 29 is secured to the outer limb of the arch 26 in order to counterbalance the inner arm of the bar 18 and the trowel 20, so that the trowel 20 will 20 not rest too heavily on the soft concrete when the hands are removed from the rods 28.

The grooving device is readily moved along the rail at one side of the road so as 25 to produce an accurate groove which is parallel with the corresponding edge of the road. The pressure of the trowel on the concrete may be regulated by tilting the truck 30 transversely on the rail, it being apparent that the trowel may be raised and lowered by depressing and raising the handle rods 28, the wheels 14 tilting laterally on the rail.

Fig. 4 illustrates a modified construction of the grooving device, which combines therewith a transverse bridge to extend across the concrete and support workmen. Thus, a transverse board or platform 18' extends across the road, and has one end secured on the beam 13' mounted on the 40 wheels 14', and the opposite terminal of the platform is secured on short beams 30 carrying axles 31 on which wheels 32 are mounted. The wheels 32 are similar to the wheels 14' to move on the opposite rail, and said wheels 32 may be adjusted transversely on the axles 31 for roads of different widths, or when negotiating curves in the road. The platform 18' is braced against depression by the latticework 26', or other suitable stiffening 45 structure. The wheels 32 need not be spaced apart so far as the wheels 14', inasmuch as the wheels 14' will avoid the tendency for the device to turn off the rails. A handle rod 28' is secured to the lattice work 26' 50 above the beam 13' and extends beyond said beam for moving the truck by hand.

The trowel 20' comprises the top piece 21' having its end portions 22' bent back downwardly, and the shoe 23' is secured to said 60 end portions 22' and is resilient and curved so as to be capable of yielding on the concrete. The shoe 23' has the grooving rib 24'. One end of the shoe 20' is hingedly connected, as at 33, to a support 34 fastened 65 by a bolt 35 or otherwise to the platform 18',

said platform having a row of apertures 36 for adjusting the trowel 20' transversely for roads of different widths, although other adjustable supporting means for the trowel may be used. The other end of the trowel 70 is connected by a coiled spring 37 with an arm 38 mounted on a rock shaft 39 journaled in bearings 40 at one edge of the platform 18', the arm 38 being secured on the shaft 39 by means of a set screw 41 or the like, so that 75 said arm may be loosened for adjusting the trowel. The spring 37 surrounds a rod 37' pivoted to the top piece 21' and slidable through the arm 38, and said rod has a head at its upper end for the contact of the arm 80 when the arm is raised, so as to raise the trowel 20'. When the arm 38 is moved downwardly, the spring 37 is compressed with the desired pressure to press the trowel 85 on the concrete with more or less pressure as desired. A hand lever 42 is secured to the rock shaft 39 at the side of the device where the beam 13' is located, in order that said 90 lever may be conveniently swung by the operator for raising and lowering the trowel. The lever 42 carries a dog 43 to engage a notched segment 44 carried by the beam 13' to maintain the trowel in its adjusted position.

With this device the trowel is raised and 95 lowered by moving the lever 42, and the platform 18' may also support workmen in finishing the surface of the concrete either along the division line or between said line and the sides of the road.

Fig. 5 illustrates a division plate or strip 8^a having a plate 50 riveted or otherwise secured to one side thereof at each end, and said plates have the depending sharpened or pointed portions 51 to enter the ground, 100 thereby providing end stakes or pegs to enter the ground for holding the ends of the plate or strip in position. In order to hold the plate or strip 8^a on the ground, a stake 9^a is driven down into the ground at one side of 105 the strip and has a hook 52 at its upper end to engage over the upper edge of the strip.

Fig. 6 illustrates the use of a division plate or strip 8^b which is of curved cross-section, and which is preferably supported 115 above the ground or sub-base, so that when the concrete sets it will crack between the upper edge of said strip and the groove 12, and between the lower edge of said strip and the ground or sub-base, thereby forming the 120 opposite slabs or sections with an interlocking tongue and groove defined by the strip 8^b. In order to support the strip 8^b, the stake 9^b which is driven into the ground may have an offset or seat 53 to support the strip, 125 said strip having apertures through which the upper terminal of the stake passes.

Fig. 7 illustrates the stake 9^b used with the strip 8 which is flat, for supporting the strip 8 above the ground.

Having thus described the invention, what is claimed as new is:—

1. A concrete grooving device comprising a truck having wheels to move on a side rail defining the edge of a concrete road under construction, an inwardly extending bar mounted on said truck, said truck being adapted to be tilted transversely on the rail for raising and lowering said bar, a grooving tool carried by said bar, and a handle member connected to the truck and extending outwardly therefrom for moving the truck on the rail and tilting the truck transversely.
- 15 2. A concrete grooving device comprising a truck having wheels to move on a side rail defining the edge of a concrete road under construction, an inwardly extending bar mounted on said truck, said truck being adapted to be tilted transversely on the rail for raising and lowering said bar, a grooving tool carried by said bar, and a weight connected to the truck at the outer side thereof to counterbalance said bar and tool.
- 25 3. A concrete grooving device comprising a truck having wheels to move on a side rail defining the edge of a concrete road under construction, a bar extending across and secured to the truck to project inwardly and outwardly therefrom, a grooving tool carried by the inner arm of said bar, and a handle member and counterbalancing weight mounted on the outer arm of said bar.
- 35 4. A concrete grooving trowel comprising a top piece and a curved resilient shoe secured at its ends to the top piece, said shoe having a longitudinal rib on its lower surface.
5. A concrete grooving trowel comprising a top piece having end portions bent back downwardly, and a curved resilient shoe secured to said end portions and having a longitudinal rib on its lower surface.
6. A truck to move on the rails defining the side edges of a road under construction, having means for finishing the concrete, and having a wheel to move on one of said rails, and a disk secured to the inner side of said wheel having its edge projecting beyond the periphery of said wheel to overlap said rail and having its edge portion formed to round off the corresponding edge of the concrete.
7. A concrete grooving device comprising a truck movable on the side rails defining the edges of a concrete road under construction, and a grooving tool carried by the truck having a shoe with a rounded surface to move on the concrete and provided with a longitudinal rib on the surface thereof to form a groove in the concrete.
8. A concrete grooving device comprising a truck having wheels to move on a side rail defining the edge of a concrete road under construction, a grooving tool supported from said truck to move on plastic concrete, said truck being adapted to be tilted transversely on the rail for raising and lowering said tool, and a handle member carried by the truck for conveniently moving the truck on the side rail and tilting the truck.

In testimony whereof I hereunto affix my signature.

JOSEPH WILLIAM HELTZEL.
